[57] CLAIM

The ornamental design for a display cover, as shown and described.

DESCRIPTION

FIG. 1 is a perspective view of a display cover showing my new design;

FIG. 2 is a perspective view thereof in a closed condition;

FIG. 3 is an enlarged front elevational view thereof;

FIG. 4 is a top plan view thereof;

FIG. 5 is a bottom plan view thereof;

FIG. 6 is a rear elevational view thereof; and,

FIG. 7 is a side elevational view thereof, the opposite side being a mirror image thereof.

The broken line shown on FIGS. 1 and 2 is for illustrative purposes only and forms no part of the claimed design.
